WINFRED N. LURCOTT, OF ELIZABETH, NEW JERSEY

DRAFT REGULATING APPARATUS FOR FURNACES

Application filed January 23, 1932. Serial No. 583,438.

Among the principal objects which the present invention has in view are: To provide simple and efficient means for controlling the drafts of a furnace in response to thermostatic conditions; to simplify the construction and arrangement of apparatus to effect the above stated purpose; and to adapt the apparatus for installation on various styles of damper controlling devices.

10 Drawings:

Figure 1 is a side elevation of a furnace of the usual type showing in conjunction therewith a draft regulating apparatus constructed and arranged in accordance with the present invention.

Figure 2 is a schematic view showing an end view of the apparatus and diagram of a thermostatic switch and wiring connecting same with the draft regulating apparatus.

20 Figure 3 is a side view of the interior of the apparatus, the side cover having been removed to show the interior elements.

Figure 4 is a horizontal section of the same, the section being taken as on the line 4—4 in 25 Figure 3.

Figure 5 is a detailed view showing a fragment of a transmission element used in the motor herein described, together with a fragment of the engaging elements by which the 30 said transmission element is moved.

The present apparatus is employed to open and close the draft dampers under pre-arranged heat conditions desired for the furnace. With this end in view the furnace is 35 provided with a rod 9 which is pivoted on a standard 10 disposed in convenient location upon the furnace X.

To one end of the rod 9 is attached, by 40 means of a cable 11, the damper door 12. The weight of the door and parts connected therewith are counter-balanced by adjustable weight members 13 which usually slide lengthwise of the rod 9 until a balance is established. The movement of the rod 9 is guided by 45 means of a bifurcated guide member 14.

In the present apparatus the rod 9 becomes what might be termed a teeter and the disturbance of its equilibrium is what the work performed depends on. To this end a yoke 50 15 forms an upwardly extending arch. The

lower extremities of this arch are rigidly connected to the rod 9. The horizontal member of the yoke 15 forms a track on which the rollers 16 travel. The rollers 16 are used to suspend the weighted casing 17 within which 55 are mounted the mechanism for causing the said casing to travel back and forth lengthwise of the said yoke 15, thereby eliminating placing its weight at one side or the other of the standard 10 and so over-balancing the rod 60 9 to open and close the door 12.

Within the casing is mounted the shaft 18 upon which is mounted the gear wheel 19. The wheel 19 is used to rotate the shaft 18 and thereby turn a crank 20 which is rigidly 65 attached to the said shaft. The crank 20 is in turn connected by means of a link 21 with an arm 22 set out from one of the uprights of the yoke 15.

It is obvious that as the wheel 19 and the 70 shaft 18 connected therewith rotate, the crank 20 is swung around in a circle. To do this the link 21 being anchored to the stationary arm 22 to swing thereon, results in the crank 20 becoming an arm that alternately pushes 75 or pulls the casing 17 lengthwise of the yoke 15.

The gear wheel 19 is driven by means of the 80 small pinion 23 which is fast to a drum 24. The drum 24 has an extension flange 25 which is loosely engaged by the arm 26 when moved away from the magnet 30, a slot 27 being cut edgewise therein to loosely engage the said flange during such movement. The arm 26 is mounted upon a spring member 28 which is 85 tensioned to press the arm 26 upon the flange to frictionally engage the same. The spring 28 is connected with an armature 29 held in position to be operated upon by the magnets 30 when the same are energized.

The slot 27 is sufficiently wide to fit the flange 25 loosely but to engage the same by being rocked to grip the flange when and as the armature 29 is drawn toward the magnets 30.

In the forward position as shown in Figure 3 of the drawings, the slot 27 does not engage the flange 25 but it is in a position to do so if the arm 29 is drawn toward the magnet 30. The armature 29 is spring-actuated 100

to normally assume the position as in Figure 3. Whenever the current is suspended in the magnets 30, the armature 29 assumes the position shown in Figure 3 the arm 26 having glided over the flange 25 without gripping the same.

The spring member 28 holds the arm 26 pressed against the flange 25 ready to grip the same on its being retracted. As a result of this, a backward and forward movement or reciprocation when imparted to the arm 26, as shown by the double-headed arrow in Figure 3 causes the drum 24 to rotate.

A rapid series of releases and engagements by the arm 26 on the flange 25 resulting from the action of the magnet 30 produces a revolution of the drum 24 and the pinion 23 connected therewith. It will be observed that this movement is always in one direction, producing thereby a constant or one-way revolution for the wheel 19 and the crank 20 connected therewith when activated.

It will be observed that as the crank swings above the horizontal, the casing 17 is moved in one direction whereas when the crank is swung below the horizontal, the casing is swung in the opposite direction, the extremes of the two travels being at opposite sides of the pivotal mounting on the standard 10. The rod 9 is over-balanced by the weight of the casing 17 and associated parts, with the result that the damper door 12 is opened or closed to increase or diminish the draft on the furnace.

The electrical energy imparted to the magnets 30 corresponds with the movement of the thermostatic blade 31, which is mounted in a casing 32 located in any convenient position at a point removed from the furnace. The blade 31 travels between the switch contacts 33 and 34. The said contacts are in circuit with lines 35 and 36 respectively. These lines are connected to the binding posts 37 and 38 respectively. The binding posts 37 and 38 are in electrical contact with the spring blades 39 and 40, shown best in Figure 3 of the drawings. The ends of the blades 39 and 40 rest normally upon the metal bushing 41, through which current is conveyed to the casing 17 and through the casing 17 to the wire 42 and magnets 30.

Mounted upon the bushing 41 is an insulating sector 43. The sector 43 is in the path of the blades 39 and 40, and operates to discontinue current received through the said blades alternately thereby inserting a half complete revolution of the gear 19 and of the crank 20.

The device is best operated by an alternating current employing a bell transformer 44. One of the terminals in the transformer 44 is connected by means of a wire 45 with the casing 32. The other terminal of the transformer is connected by means of the wire 46 with a binding post 47, which in turn is

connected by means of a wire 48 with the magnets 30.

When the parts are arranged as above described and as shown in the drawings, the operation is as follows:

Presuming that the thermostatic blade has been carried into contact with the switch 34, the current is thereby established through the line 36, binding post 38, the blade 40, the bushing 41, casing 17, wire 42, magnets 30, wire 48, binding post 47, wire 46, transformer 44, wire 45, thus completing the circuit. The circuit being thus completed, the armature 29 is rapidly attracted to and released from the magnets 30 in correspondence with the phases of the alternating current employed. As the armature 29 is thus vibrated, the arm 26 is swung to and from the magnet with the result that the drum 24 is moved thereby as many revolutions as is necessary for the pinion 23 to rotate the gear wheel 19 until the insulating sector 43 passes under the blade 40, or in other words, until the gear wheel 19 has made a half complete revolution. The sector 43 thus breaking the circuit, the casing 17 and parts connected therewith are brought to a stand.

If this operation has opened the door 12, the parts will so remain until the temperature blade 31 may contact with the switch 34. When the heat is above the predetermined point, the blade 31 is moved to contact with the switch 33, with the result that now the blade 39 and electrical parts connected therewith are energized. The blade 39 now resting on the metallic portion of the bushing 41, the magnets 30 are operated as above described until the sector 43 in the course of its travel passes under the blade 39, thereby arresting the flow of current and the operation of the magnets 30.

While I have herein shown and described the apparatus as employing alternating current, it will be understood that a direct and/or battery current could be used, employing any suitable contact breaker or oscillator in conjunction therewith to attain the object of vibrating any current excitation in the magnets 30.

I claim:

1. In draft regulating apparatus for furnaces, the combination with a pivotally balanced member operatively connected with a furnace draft regulating member, an apparatus for rocking said balanced member comprising an automotive weight member supported by said balanced member, said weight member being adapted to move successively in opposite directions to affect the balance of said balance member by the weight of said weight member.

2. In draft regulating apparatus for furnaces, the combination with a pivotally balanced member operatively connected with a draft regulating member, an apparatus for

rocking said balanced member comprising a weight member supported by said balanced member and embodying means carried by said weight member for moving said weight member successively in opposite directions 5 to affect the rocking moment of said balanced member by the weight of said weight member.

3. In draft regulating apparatus for furnaces, the combination with a pivotally balanced member operatively connected with a draft regulating furnace door, an apparatus for rocking said balanced member, said apparatus comprising, a weight member movably mounted upon said balanced member 10 for travel thereon to opposite sides of the pivot thereof, electro-mechanical means for moving said weight member reciprocatively upon said balanced member, said means embodying an electro-magnet and vibratory armature therefor, suitable gearing for moving said weighted member, and means attached to said armature for operatively engaging said gearing when and as said armature is moved by said magnet.

4. In draft regulating apparatus for furnaces, the combination with a pivotally balanced member operatively connected with a draft regulating furnace door, an apparatus for rocking said balanced member, said apparatus comprising, a weight member movably mounted upon said balanced member for travel thereon to opposite sides of the pivot thereof, electro-mechanical means for moving 15 said weight member reciprocatively upon said balanced member, said means embodying, a crank and shaft therefor mounted upon said weighted member, means connecting said crank and stationary member in a manner to necessitate the movement of said weight member when said crank is moved about said shaft, a gear train operatively connected with said shaft to rotate the same, an electro-magnet and vibratory armature therefor mounted in said weight member, means attached to said armature for operatively engaging 20 said gears when and as said armature is moved toward said magnet, means attached to said armature for operatively engaging said gears when and as said armature is moved by said magnet, and for supplying current to said magnet, said means embodying a plurality of supply switches, means associated with said shaft for breaking the contact of one of said switches in correspondence with the half revolution of said shaft and crank attached thereto, and means for interrupting the current supplied to said magnet.

5. In draft regulating apparatus for furnaces, the combination with a pivotally balanced member operatively connected with a draft regulating furnace door, an apparatus for rocking said balanced member, said apparatus comprising, a weight member movably mounted upon said balanced member for travel thereon to opposite sides of the pivot thereof, electromechanical means for moving 25 said weighted member reciprocatively upon said balanced member, said means embodying, a crank and shaft therefor mounted upon said weight member, means connecting said crank and stationary member in a manner to necessitate the movement of said weighted member when said crank is moved about said shaft, a gear train operatively connected with

said shaft to rotate the same, an electro-magnet and vibratory armature therefor mounted in said weight member, means attached to said armature for operatively engaging said gears when and as said armature 70 is moved by said magnet, and means for supplying current to said magnet, said means embodying a plurality of supply switches, and means associated with said shaft for breaking the contact of one of said switches 75 in correspondence with the half revolution of said shaft and crank attached thereto.

6. In draft regulating apparatus for furnaces, the combination with a pivotally balanced member operatively connected with a draft regulating furnace door, an apparatus for rocking said balanced member, said apparatus comprising, a weight member movably mounted upon said balanced member for travel thereon to opposite sides of the pivot 80 thereof, electromechanical means for moving said weight member reciprocatively upon said balanced member, said means embodying a crank and shaft therefor mounted upon said weight member, means connecting said 85 crank and stationary member in a manner to necessitate the movement of said weighted member when said crank is moved about said shaft, a gear train operatively connected with said shaft to rotate the same, an electromagnet and vibratory armature therefor mounted in said weight member, means attached to said armature for operatively engaging 90 said gears when and as said armature is moved toward said magnet, means attached to said armature for operatively engaging said gears when and as said armature is moved by said magnet, and for supplying current to said magnet, said means embodying a plurality of supply switches, means associated with said shaft for breaking the contact of one of said switches in correspondence with the half revolution of said shaft and crank attached thereto, and means for interrupting the current supplied to said magnet. 95
